WINDING TENSION APPARATUS

Michael Gravatt Jones, Fredericksburg, Va., assignor to American Viscose Corporation, Philadelphia, Pa., a corporation of Delaware

Application February 5, 1952, Serial No. 269,926

3 Claims. (Cl. 318—6)

1

This invention relates to winding and reeling apparatus and more particularly to apparatus for winding material onto a storage device, particularly a winding core, wherein the application of winding tension may be conveniently and accurately controlled.

During the winding operation of a material such as a filamentary bundle, sheet or film and particularly heavy packages or beams thereof onto a storage device, the application of an improper amount of tension often causes various undesirable effects such as deformation of the storage package. It has been found that package deformation may be minimized and that best winding results may be obtained by maintaining a constant tension upon the material during the winding operation or by slightly diminishing the same continuously and progressively as the material package builds outwardly from its core.

Heretofore various control systems have been devised which purport to maintain a constant winding tension as the material package builds up on the storage device. Some of these systems merely strive to maintain the angular velocity of the winding motor constant but such systems have been found unsatisfactory since as the diameter of the material package increases the peripheral velocity thereof and the material winding tension likewise simultaneously increase. Other control systems have been suggested wherein the armature current applied to an electrical winding motor is maintained constant. It is reasoned that, since the power output of the motor is proportional to the armature current supplied thereto, a constant power output and winding tension may be obtained by maintaining a constant motor armature current. One such electrical control system, of which the present invention is an improvement, includes a generator whose armature output circuit supplies energizing current to the material winding motor and whose output voltage is controlled by regulating the generator field excitation in accordance with the voltage drop across a series resistor in the generator output circuit. Thus, in the operation of this system, as the diameter of the material package increases, the winding motor torque increases, greater current tends to flow in the generator output circuit, a greater voltage drop across the series resistor is produced, more lines of force are created which oppose the regular energizing field of the generator and a smaller resultant generator voltage tends to maintain a constant armature current thereby reducing the speed of the motor and purportedly maintaining

2

constant winding tension in the filamentary material.

It has been found, however, that increased winding tension is produced in this type of control system particularly when relatively heavy packages, such as rolls of cellophane, paper, etc., and warp beams are being wound. As the material package builds outwardly from its core during the winding operation and the speed (R. P. M.) of the winding motor is decreased to maintain the peripheral speed of the package substantially constant, frictional losses in the winding motor and the take-up roll also decrease. Thus, although the torque developed by the motor 10 may be theoretically maintained constant by controlling the magnitude of its armature current, less frictional forces are present to oppose the same and greater rotational energy is made available to produce increased tension in the 15 material being wound. In the present system, however, the torque developed by the motor must be somewhat increased simultaneously with decrease in rotational speed to achieve a condition of constant web feed and constant web 20 tension.

It is a principal object of the present invention to provide an electrical control system for winding apparatus wherein the tension developed in a material which is being wound upon a core may be conveniently and accurately maintained constant or controlled.

The accompanying drawing discloses a circuit diagram of winding control apparatus which is operative in accordance with a preferred embodiment of the present invention. As illustrated 35 therein a material 3, such as a filament yarn, a warp sheet, and a film or sheet, such as cellophane progresses at a constant rate from a suitable source not shown on the drawing about the liquid treating or drying drums 4, 5 and 6 to the take-up device 8 comprising a winding core 8a. The core of the take-up device 8 is mechanically 40 connected by the shaft 9 to the motor M1 which drives the device 8 and determines the degree of tension applied to the material as it is wound thereon.

The three-phase motor M2 is energized from a suitable source not shown on the drawing through the control switch 17. Shaft 18 which is driven 45 by motor M2 is mechanically coupled to the armature of the exciter E, the control generator CG, and the main generator MG.

The exciter E provides an independent direct current source for the control system and includes a shunt field winding 19 and a series field

winding 28. The variable resistor 21 is provided in the shunt field winding circuit to permit control of the exciter generator at its output terminals 22 and 23.

The armature of motor M1 is energized by the main generator MG through a circuit which may be traced from the generator terminal 10, through conductor 11, resistor 12, conductor 13, motor M1, conductor 14, contact 15, to the other generator terminal 16. The separately excited field winding 24 of motor M1 is energized by a circuit which is connected to the output terminals 22 and 23 of the exciter E and includes the variable resistor 25.

The field winding 26 of the main generator MG is energized by the control generator CG by a circuit which may be traced from the terminal 27 of the control generator through conductor 28, variable resistor 29, field winding 26, conductor 30, series field winding 31 to the opposite terminal 32 of the control generator.

In addition to the series winding 31 already mentioned, the field circuit of the control generator is energized by four other field windings which may be called the anti-hunt field, the pattern field, the differential field and the cumulative field. The anti-hunt field winding 33 is connected in series with the variable resistor 34 across the output terminals 27 and 32 of the control generator and tends to stabilize its voltage output.

The pattern field winding 35 of the control generator is provided with a pair of parallel energizing circuits. By one circuit it is energized by the output voltage of the exciter generator E which may be traced from the terminal 23, through conductor 40, variable resistor 45, relay contact 41, the pattern field winding, conductor 42, relay contact 43, conductor 44 to exciter terminal 22. By the other circuit the pattern field winding of the control generator is energized by the output voltage of the main generator MG from the terminal 10 through conductor 45, variable resistor 46, relay contact 47, the pattern field winding, conductor 48, relay contact 49 to the opposite generator terminal 16.

The differential field winding 50 of the control generator and the series variable resistor 51 are energized by the voltage across the potentiometer 52 which therefore is proportional to the magnitude of armature current which is supplied to the motor M1 as will be more fully described hereinafter.

Cumulative control generator field winding 52 is also provided with a pair of parallel energizing circuits. By one of these circuits it is energized by the output voltage of the pilot generator PG which is coupled by the shaft 36 to the drying drum 6. This circuit may be traced from terminal 37 of the pilot generator through conductor 38, relay contact 53, conductor 60, the cumulative winding, conductors 59 and 82, relay contact 39, conductor 54, variable resistor 76, to the opposite pilot generator terminal 55. By the other circuit the cumulative field winding of the control generator circuit is energized by the armature voltage of motor M1. This circuit may be traced from the armature terminal 56 of the motor through conductors 14 and 57, relay contact 58, conductor 59, the cumulative winding, conductor 60, relay contact 62, conductor 63, potentiometer 64 to the opposite armature terminal motor 65.

The various relay contacts mentioned hereinbefore are controlled by their respective relays which may be selectively energized by the exciter direct current source when their manually op-

erable switches are closed. Thus, the main relay M may be energized when the manually operable switch 66 is closed and its associated contact 15 may be thereby closed to apply the output voltage of the main generator MG to the motor M1.

In a similar manner the speed relay S may be energized by the exciter E when contact 69 is closed and when its associated manually operable switch 67 is closed. Upon its energization its normally open back contacts 47, 49, 39 and 53 all close and the speed of the motor M1 may be synchronized with the rate of travel of the material 3 as will be more fully explained hereinafter.

When relay T is energized by a circuit which extends from the terminals of exciter E thereto through the manual switch 68 and back contact 70 of relay S the control generator pattern field is connected to the terminals of the exciter E. Relay T1 which is effectively in parallel with relay T may be energized when its manually operable switch 71 is depressed thereby placing the cumulative winding of the control generator across the armature of the motor M1 through contacts 58 and 62.

It is to be noted that contact 69 of relay T and contact 70 of relay S provide an interlocking means whereby neither of these relays can be energized while the other is energized.

In describing the operation of the winding control system of the present invention it will be first assumed that it is desired to wrap the material about an empty reel or take-up device 8. It has been found that when the peripheral speed of the take-up device 8 is made to correspond to the rate at which the material is fed thereto, the wrapping operation is greatly simplified. To accomplish this the operator closes manual switch 67 to energize the speed relay S through the normally closed back contact 69 of relay T. Closure of its contacts 47, 49, 39 and 53 places the control generator pattern field 35 across the output terminal of the main generator MG and the control generator cumulative field winding 52 across the output terminals of the pilot generator PG thereby providing an additional field excitation source for the control generator. In this way by suitable adjustment of the variable resistor 76 in the cumulative field circuit, the output voltages of the control generator and the main generator and the speed of motor M1 may be properly built up so as to facilitate the lacing operation. This may occur should the web break, in which event the apparatus is laced up at speed.

Once the material has been properly wrapped upon the take-up device 8, it is desirable to thereafter control the speed of motor M1 such that as the package builds up and as the peripheral velocity tends to increase the tension is prevented from likewise increasing. To accomplish this the manually operable switch 67 in the speed relay energizing circuit is opened and the manually operable switches 68 and 71 are depressed to energize the associated relays T and T1. Closure of contacts 41 and 43 of relay T places the pattern field winding of the control generator across the output terminals of the exciter E and closure of contacts 58 and 62 of relay T1 places the control generator cumulative field winding across the armature terminals of motor M1.

With the field circuit of the control generator energized in this manner, the speed of motor M1 may be controlled such that either a constant or a drooping tension characteristic may be obtained. Thus since the differential field 50 op-

poses the field created by the pattern field 35, increases in armature current applied to motor M1 increase the voltage drop across the series resistor 12 and the current through the differential field thereby diminishes still further the resultant control generator field and consequently the output voltage of main generator G.

As stated hereinbefore, however, as the rotational speed of the motor M1 decreases with the build-up of the package, reduced frictional losses do not affect the magnitude of the motor armature current and therefore the tension improperly increases although the armature current of the motor and its developed power are maintained constant. For this reason the cumulative field winding 52 has been provided in the present system to further affect the ultimate speed of motor M1. The strength of the cumulative field is therefore adjusted such that it aids the control generator pattern field. As the diameter of the package increases and the rotational velocity of the motor is decreased, as hereinbefore discussed, less back electromotive force is generated by the motor M1, less voltage is available to energize the cumulative field to aid the pattern field and therefore the output of the main generator MG and the rotational speed of the motor are properly further decreased so that the peripheral speed of the motor and take-up roll are maintained substantially constant.

The series field winding 31 of the control generator is adapted to amplify changes produced therein by the differential field. The series variable resistor 29 in the control generator operates on the straight line portion of its saturation curve and thereby provides a linear amplification characteristic. The anti-hunt field which is connected across the output terminals of the control generator CG is provided merely to dampen the oscillatory tendency of the control system.

It is to be noted that the present novel and improved control system provides a means whereby the actual tension produced may be accurately maintained constant or, if desired, may be controlled to diminish slightly as the package builds up.

Although the preferred embodiment of the present invention has been disclosed in connection with winding materials such as yarns, sheets or films, it is to be understood that the system may be employed for winding any material upon a storage device without departing from the spirit or scope of the invention.

While preferred embodiments of the invention have been disclosed, the description is intended to be illustrative only, and it is to be understood that changes and variations may be made without departing from the spirit and scope of the invention as defined by the appended claims.

I claim:

1. A control system for driving a web take-up roll under conditions of constant peripheral speed and constant web tension as the roll builds up, comprising a take-up roll, a motor for driving said take-up roll, a main generator for supplying current to the armature of said motor, a field winding for said generator, a control generator for energizing said main generator field winding, a direct driving connection between the control generator and the main generator, a series field winding for the control generator, a shunt field winding for the control generator, a differential field winding for the control generator, a pattern field winding for the control generator, a cumulative field winding for the control generator, a

source of substantially constant voltage direct current, a pilot generator, a constant speed driving connection for the pilot generator, a circuit for connecting the pattern field across the constant voltage direct current supply, a circuit for connecting the pattern field across the armature of the main generator, means including a relay for selectively connecting and disconnecting said circuits to the pattern field, a circuit for connecting the cumulative field to the pilot generator, a circuit for connecting the cumulative field across the armature of the motor, and means including a relay for selectively connecting and disconnecting said last-named circuits to the cumulative field.

2. A control system for driving a web take-up roll under conditions of constant peripheral speed and constant web tension as the roll builds up, comprising a take-up roll, a motor for driving said take-up roll, a main generator for supplying current to the armature of said motor, a field winding for said generator, a control generator for energizing said main generator field winding, a direct driving connection between the control generator and the main generator, a series field winding for the control generator, a shunt field winding for the control generator, a differential field winding for the control generator, a pattern field winding for the control generator, a cumulative field winding for the control generator, a source of substantially constant voltage direct current, a pilot generator, a constant speed driving connection for the pilot generator, a circuit for connecting the pattern field across the constant voltage direct current supply, a circuit for connecting the pattern field across the armature of the main generator, relay means for selectively connecting and disconnecting said circuits to the pattern field, a circuit for connecting the cumulative field to the pilot generator, a circuit for connecting the cumulative field across the armature of the motor, whereby the strength of the cumulative field is adjustable to oppose the differential field, and relay means for selectively connecting and disconnecting said last-named circuits to the cumulative field.

3. A control system for driving a web take-up roll under conditions of constant peripheral speed and constant web tension as the roll builds up, comprising a take-up roll, a motor for driving said take-up roll, a main generator for supplying current to the armature of said motor, a field winding for said generator, a control generator for energizing said main generator field winding, a direct driving connection between the control generator and the main generator, a series field winding for the control generator, a shunt field winding for the control generator, a differential field winding for the control generator, a pattern field winding for the control generator, a cumulative field winding for the control generator, a source of substantially constant voltage direct current, a pilot generator, a constant speed driving connection for the pilot generator, a circuit for connecting the pattern field across the constant voltage direct current supply, a circuit for connecting the pattern field across the armature of the main generator, relay means for selectively connecting and disconnecting said circuits to the pattern field, a circuit for connecting the cumulative field to the pilot generator, a circuit for connecting the cumulative field across the armature of the motor, a

field across the armature of the motor, means including a variable potentiometer in the circuit connecting the cumulative field across the armature of the motor whereby the strength of the cumulative field is adjustable to assist the pattern field, and relay means for selectively connecting and disconnecting said last-named circuits to the cumulative field.
